HEEL

Herbert Levine, New York, N. Y.

Application September 2, 1954, Serial No. 453,735

1 Claim. (Cl. 36—34)

This invention relates to improvements in women's 15 heels.

Women's heels often undergo structural failure, generally in two regions. Firstly at the heel support, which is connected to the body of the shoe by nails or the like, the axial penetration of the nails causes the material, 20 generally wood, to split or shear off laterally.

Secondly transverse forces acting on the shank either shear the shank end off or cause axial rupture due to bending stresses.

Inasmuch as wood is a granular material, the grains should be deployed in such a manner as to inhibit the above described failures. If the grains are arranged parallel to the axis throughout the heel, the bending and shearing stresses induced by the transverse forces will be most effectively resisted. However, such a grain arrangement is least effective in resisting rupture and failure due to the axial entry of nails or the like into the heel support area. Conversely the arrangement of the grains normal to the heel axis results in weakness against the stresses induced by transverse forces and a maximum resistance against the stresses induced by the hammering of an axial nail into the heel support.

Since conventionally, heels are made from materials particularly wood, in which the grains run in one direction throughout, or material having non-uniform strength axially and transversely, the resultant heel cannot effectively resist both the rupturing effects discussed supra.

Frequently women object to the location of a rubber heel at the shank base. However to eliminate the rubber heel is also objectionable since the heel serves to dampen the impact from the floor to the user's foot.

Consequently it is the dual inventive object to provide an improved heel which, effectively resists both the transverse forces acting on the heel and the rupturing stresses induced by the entry of an axial nail into the heel support, and also which provides an elastic cushion within the heel assembly eliminating the need for a rubber heel at the shank base, the arrangement being such as to facilitate the shaping of the heel to properly fit the contours of a woman's shoe.

A further inventive object is the provision of a heel assembly comprised of materials providing both maximum structural resistance to the stresses resulting from the entry of a nail into the heel support and to the transverse forces acting on the heel.

A still further inventive object is the provision of a heel assembly which comprises a granular material whose grains are parallel to the heel axis near the shank and normal to the heel axis near the heel support.

A still further inventive object is the provision of a heel assembly which comprises a granular structure whose grains are parallel to the heel axis from the shank to the surface adjacent the shoe and includes grains normal to the heel axis forming the heel support encompassing the upper portions of the first described grains.

A still further inventive object is to provide a heel assembly with a non-uniform granular material wherein

2

the upper grains are normal to the heel axis and encompass grains running parallel to the heel axis, the parallel grains extending to form the shank and resilient material separating the interface of the differently arranged grains 5 both longitudinally and transversely.

Further objects and inventive details will become apparent from the following detailed description when read in conjunction with the attached drawings in which:

Figure 1 is a perspective view of the improved heel 10 assembly;

Figure 2 is a longitudinal section of the heel assembly; Figure 3 is a longitudinal section of a modified form thereof;

Figure 4 is a front elevation of the heel assembly; Figure 5 is an exploded perspective of the component parts of the assembly; and

Figure 6 is a rear elevation of the heel assembly.

Referring to Figure 1, the improved heel assembly is seen to comprise the heel support 10 having an upper sloping surface 11 contoured to complement the underside of a woman's shoe. The peripheral surface 12 of the heel support 10 is shaped to properly continue the lines of the particular style shoe involved and is not necessarily confined to the shape herein depicted. In the central area of the surface 11 there is formed a bore 13 which extends axially through to the reduced bottom section 14 as better seen in Figure 5. Materials such as wood, leather, plastic, etc. can well be used. If a granular material, preferably such as wood, is used then the grains 16 are run in a direction normal to the longitudinal heel axis. On the other hand, when the other cited materials are used, the substance forming the material should be so arranged relative to the heel axis that, the maximum resistance to rupturing forces caused by the entry of a nail or the like, is provided. Obviously with the grains disposed normal to the axis, the granular material forming the heel support affords maximum structural resistance to axially driven nails.

Referring now to Figure 5, the lower portion of the heel assembly is seen to comprise the heel shank 18 having breast portion 17, the outer peripheral surfaces of the shank being also shaped to complete the proper contours of a woman's shoe. A transverse connection surface 19 is formed at the upper shank portion 18 from which projects axially upward towards the heel support

45 a cylindrical projection or post 21. The axis of this projection is so located relative to surface 19 that when projection 21 is snugly fitted within bore 13, the contours of the heel support, the breast and the shank portions intersect to form a smoothly continuous contoured woman's heel. When wood or other granular materials are used for fabricating the shank, the grains 22 are directed parallel to the heel axis affording maximum structural resistance to transverse forces. For example the shearing strength normal to the grain can be as much as twice the shearing stress parallel to the grain. Moreover in tension due to bending when the tension is parallel to the grain (as in the instant case) the allowable stress may be as much as 6 to 7 times that when the tension is normal to the grains. Roughly then we can estimate that the shank assembly is approximately 4 times the strength of an equivalent assembly having the grains normal to the axis.

60 Returning to the heel support, since failures due to the entry of an axial nail are primarily shear failures, by having the grains normal to the axis the resultant shear resistance can be doubled.

Practically this results in fewer failures when the heel is attached to the shoe and breakages due to snubbing the heel against floors, chairs, etc.

70 For additional structural capacity and also comfort

3

as better seen in Figure 2, there is provided a layer of resilient material comprising the cylindrical portion 23 encompassing the projection 21 and contacting the bore 13 of the heel support. A further resilient layer 24 is provided between the lower section 14 of the heel support and the surface 19.

The resilient layers 23 and 24 function to dampen the impact transmitted from the heel shank 18 to the heel support 10 thereby increasing the user's comfort and reducing the impact stresses between the heel support and the breast. Furthermore when the resilient layer is a cementitious compound, the layer binds the parts together.

In Figure 5 the resilient layers are shown in the form of the pre-formed resilient inserts 25 and 26 which can be formed of rubber or the like. It should be however understood that other forms of resilient layers can be effectively used such as rubber cement, caulking compounds, etc. Thus the illustrated forms 25 and 26 should not be construed as restrictive.

In Figure 3 there is depicted a further modification wherein a resilient layer is interposed only between the heel support 10 and the shank 18 for cushioning vertical impacts. The resilient layers also serve to hold the assembly together.

Due to the structural arrangement disclosed it is apparent that the aesthetic features of an extremely thin woman's heel can be maintained without increasing fabrication costs. The resultant heel is, on the average 4 times stronger than the conventional designs and provides a comfortable resilient heel action.

It should be further understood that variations in shape, size, material, and the positioning of the combinative elements are all within the inventive scope disclosed herein.

4

Having thus disclosed in detail the nature of the invention, I claim:

A heel assembly comprising an upper heel support portion adapted for connection to a woman's shoe in combination with a lower portion, said upper heel support portion comprising a fibrous material shaped to fit the contours of a woman's shoe whose grains are normal to the heel axis and including an axial bore, said lower portion comprising a fibrous material whose grains are parallel to the heel axis and whose periphery continues the contours of the heel support, said upper heel support portion and said lower portion including transverse confronting surfaces, said lower portion including an axial projection extending through said bore from the confronting surfaces, said lower portion extending axially away from said heel support, said projection being encompassed by a rubber tube and said confronting surfaces being separated by a transverse rubber insert therebetween.
